UNITED STATES PATENT OFFICE.

R. BOEKLEN AND W. STAELHEN, OF BROOKLYN, NEW YORK.

BUTTON OR GARMENT-FASTENER.

Specification of Letters Patent No. 33,025, dated August 13, 1861.

To all whom it may concern:

Be it known that we, R. BOEKLEN and W. STAELHEN, both of Brooklyn, in the county of Kings and State of New York, have invented a new and useful Improvement in Garment-Fasteners; and we do hereby declare that the following is a full, clear, and exact description of the same, reference being had to the accompanying drawing, making part of this specification, in which—

Figure 1, represents a front elevation of a coat with our improved fastening, before the coat is buttoned. Fig. 2, is a similar view of the same, after the coat is buttoned. Fig. 3, is a transverse, vertical section of a modification of the same when the garment is buttoned. Fig. 4, is a similar view of the same, with the garment in the act of being unbuttoned. Fig. 5, is a front elevation of another modification of the same, when buttoned. Fig. 6, is a transverse, vertical section of the same. Fig. 7, is a front elevation of still another modification. Fig. 7*, is a transverse, vertical section of a portion of the same. Fig. 8, is a transverse, vertical section of the same. Fig. 9, is an inside view of one part of the same. Fig. 10, is a transverse, vertical section of the last-mentioned modification, when the garment is buttoned.

Similar letters of reference indicate corresponding parts in all the figures.

This invention consists in the employment or use of two disks one being attached to one and the other to the other side of a garment, and one being provided with an opening while the other is furnished with a cam of peculiar form and corresponding with the opening in the first disk, in such a manner that it may be introduced into the said opening when it is turned in a certain position, and that, when entered, it is prevented from coming out, unless brought back to the same position, (that in which it was introduced); so that, in fact, the first disk, with the opening, forms a substitute for a button-hole, and the second disk, with the cam, a substitute for a button.

To enable others skilled in the art to make and use our invention, we will proceed to describe it with reference to the drawing.

The disk, A, which takes the place of the button-hole, and which is provided with an opening, *a*, is secured to one side of a coat, or other garment, either on the outside (as

shown in Figs. 1, 2, 8 and 10), or on the inside (as shown in Figs. 3, 5 and 6); and it may be made of various shapes, in the form of a button, as shown in Fig. 1, or covered up, as shown in Fig. 8, or with a cavity, as shown in Fig. 10.

The disk, B, which takes the place of the button, and which is provided with the cam, *b*, is secured to the other side of the coat, or other garment, either in the ordinary manner—by means of thread and a needle—or in any other convenient manner, on the inside or on the outside; and the cam is either circular or oval, according to the form of the opening in the corresponding disk, A. If the opening be oval, as shown in Figs. 8 and 9, the cam may be made slightly oval or circular, but if the opening be round, as shown in Figs. 1, 2, 3 and 4, the cam only is made oval. The diameter of the cam is so proportioned in regard to the opening in the corresponding disk that it (the cam) has to be turned edgewise in order to enable it to be introduced into the opening, and when thus entered, it can only be taken out if turned back to the same position in which it was entered, so that the cam with the opening act precisely in the same manner as an ordinary button and button-hole.

If our device be properly attached to a coat or other garment, it can be buttoned up with the same facility as with the ordinary buttons and button-holes, and the labor necessary to make the button-holes and to keep them in order is obviated. In order to render the action of the cam still more secure, we have arranged it so that its lower surface is slightly inclined, as clearly shown in Figs. 3, 4, 6 and 10, the distance between the edge, *c*, of said cam being larger than that of the edge *d*. If the cam is entered into the corresponding opening, so long as the two disks remain in parallel planes, the edge, *c*, of the cam will bear on the edge of the opening, as clearly shown in Figs. 3 and 6, and if the two disks be attached to the two sides of the garment in such a manner that the disk, B, will stand slightly below the disk, A, then the cam will be forced down toward the edge, *c*, and it will remain in the position clearly represented in Fig. 3. When thus arranged, the cam will retain its position much more securely than it will if both its edges, *c*, *d*, be allowed to touch the edges of

the opening, and should it be desired to take out the cam, or in other words, to unbutton the garment, it (the cam) has to be brought to the position shown in Fig. 4, that is to say, the two disks have to be inclined toward each other more than they would have to be when the lower or inner surface of the cam is parallel to the disk to which it is attached.

10 This device forms a very simple, cheap and durable fastening for garments, and it can be used in all places where the ordinary buttons and button-holes are used.

What we claim as new and desire to secure by Letters Patent, is—

15 A button, or garment fastener, formed by the employment or use of two disks, A, B, one being provided with an opening, a, and the other with a cam, b, substantially in the manner and for the purpose specified.

R. BOEKLEN.
W. STAEHLEN.
